United States Patent Office.

GREENLEAF STACKPOLE, OF NEW YORK, N. Y., ASSIGNOR TO HIMSELF, NATHANIEL T. SPEAR, OF JERSEY CITY, NEW JERSEY, AND CYRUS AND DARIUS COBB, OF BOSTON, MASSACHUSETTS.

Letters Patent No. 63,184, dated March 26, 1867; antedated March 13, 1867.

IMPROVED MEANS FOR PROPELLING CANAL BOATS.

The Schedule referred to in these Letters Patent and making part of the same.

TO ALL WHOM IT MAY CONCERN:

Be it known that I, GREENLEAF STACKPOLE, of New York, in the county and State of New York, have invented certain new and useful improvements in the Means for Propelling Canal Boats; and I do hereby declare that the following is a full and exact description thereof, reference being had to the accompanying drawings, forming a part of this specification, in which—

Figure 1 is a side elevation.

Figure 2 is a front view; and

Figure 3 is a plan or top view of the same.

Similar letters of reference in the three views indicate corresponding parts.

This invention relates to certain improvements in that class of apparatus for propelling canal boats for which a patent was allowed to me on August 28, 1865, in which a flanged rail is used, extending along the bank of the canal, and the canal boat is provided with two wheels which bear on the flanged rail, one from above, and the other from below, clamping said rail between them in such a manner that, by imparting to said wheels a revolving motion, the canal boat is propelled.

The present improvement consists in arranging the wheels which clamp the flanged rail in a radius-arm, which swings on a shaft, and which is so constructed that it forms firm and durable bearings for the axles of said wheels. A chain, which passes over a spur-wheel mounted on the driving-shaft, extends over similar spur-wheel on the axle of one of the clamping-wheels, and by these means the motion of the driving-shaft is transmitted to the clamping-wheels, and the canal boat is propelled, and at the same time the radius-arm permits said clamping-wheels to accommodate themselves to the varying position of the canal boat, owing to the weight with which the boat is loaded, or the depth of the water in the canal. Another portion of my invention relates to an angular arm which rises and falls freely in suitable guides on the side of the boat, and is provided with a guide-wheel, which runs on the flanged rail, and serves to keep the boat parallel with said rail.

A represents a canal boat, of any desired construction, and provided with a steam engine or other suitable motor for the purpose of propelling the same. By this power a rotary motion is imparted to the shaft *a*, which extends through the side of the boat, and on which is mounted the radius-arm *b*, in such a manner that the same can freely turn on the shaft in either direction. This radius-arm is double, and between its two leaves two spur-wheels, *c d*, are situated, the spur-wheel *c* being firmly keyed to the shaft *a*, and the spur-wheel *d* is mounted on a shaft, *e*, that has its bearings in the outer end of the radius-arm *b*, as shown in the drawing. A chain, *f*, extending over the two spur-wheels, transmits the motion of the shaft *a* to the shaft *e*, and this latter shaft forms the axle for one of the clamping-wheels, *g*, which runs on the upper surface of the flanged rail *h*. The axle of the lower clamping-wheel *i* has its bearing, *p*, in a hanger, *j*, which is suspended astride the shaft *e* from a screw, *k*, that is tapped into a yoke, *l*. This yoke is supported by the shaft *e*, and by turning the screw *k* the two clamping-wheels *g i* are brought closer together or further apart, and their traction on the rail *h* is regulated at pleasure. By this arrangement the clamping-wheels are permitted to adjust themselves freely to the higher or lower position of the boat, and at the same time a firm bearing is obtained for their shafts, and the traction of said wheels can be adjusted without difficulty. The shaft *e* is in the forward part of the boat, and, in order to keep the stern in position, an angular standard, *m*, is applied to the side of the boat, being held in position by suitable guides, *n*, and arranged so that it can rise and fall freely. This rising and falling standard is armed with a wheel, *o*, which travels on the rail *h* inside its flange. By the combination of this guide-wheel with the clamping-wheels the boat is held in position parallel to the rail, and all undue strain to the clamping-wheels and rail is avoided. A spring of rubber or other suitable material may be introduced in the hanger *j*, so as to induce a yielding pressure on the rollers *g* and *i* to allow for irregularities in the thickness of the rail *h*.

I am aware that a device for propelling canal boats has been made public, in which an endless chain, impelled by the action of the engine on the canal boat, rotates a gear-wheel, or analogous device, capable of rising and sinking upon a rail fixed along the bank; but such device involved the traversing of the working parts up and down in a curved groove in the side of the canal boat, and, however carefully constructed and used,

the great strain thrown on it in propelling, and especially in reversing when under way, wrenches the apparatus and causes the parts to bind in the groove, so that they cannot play freely. My device, on the contrary, has no groove, but the shaft of the driving-wheels is put on the radius-arm *b* instead, making a very radical difference in the construction, and a great practical improvement in the working. The previous devices had also no rear guide-wheel equivalent to my guide-wheel *o*.

Having now fully described my invention, what I claim as new therein, and desire to secure by Letters Patent, is as follows:

I claim the wheels *g i* and clamp *h l*, in combination with the radius-arm *b*, horizontal driving-shaft *a*, boat *A*, and rail *h*, constructed and operating substantially as and for the purpose described.

G. STACKPOLE.
